(57) **CLAIM**

The ornamental design for an electric motorbike, as shown and described.

DESCRIPTION

FIG. 1 is a front and right side perspective view of an embodiment of an electric motorbike;

FIG. 2 is a rear and right side perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a front and right side perspective view of another embodiment of an electric motorbike;

FIG. 9 is a rear and right side perspective view thereof;

FIG. 10 is a right side elevation view thereof;

FIG. 11 is a left side elevation view thereof;

FIG. 12 is a front elevation view thereof;

FIG. 13 is a rear elevation view thereof; and,

FIG. 14 is a top plan view thereof.

The broken lines in the drawings illustrate portions of the electric motorbike that form no part of the claimed design.

1 Claim, 8 Drawing Sheets
